UNITED STATES PATENT OFFICE.

LEONARD B. SNEDEN AND HORATIO N. HOLDEN, OF HACKENSACK, N. J.

FIFTH-WHEEL FOR VEHICLES.

SPECIFICATION forming part of Letters Patent No. 326,686, dated September 22, 1885.

Application filed June 27, 1885. (No model.)

To all whom it may concern:

Be it known that we, LEONARD B. SNEDEN and HORATIO N. HOLDEN, both of Hackensack, Bergen county, in the State of New Jersey, 5 have invented an Improved Wagon-Gear, of which the following is a full, clear, and exact description, reference being made to the accompanying drawings.

Figure 1 is a front view, partly in section, 10 of our improved wagon-gear. Fig. 2 is a side view of the same, partly in section. Fig. 3 is a top view of the same.

Our invention relates to improvements in wagon-gears; and it consists in forming the 15 lower part of the head-block of metal, which is welded to the forward metallic end of the reach, independent of and above the fixed plate of the fifth-wheel.

In the drawings, A represents the head-block, 20 which we construct of two parts, the upper part, h, of wood, and the lower part, i, of metal. These two parts are firmly bolted together, as at j. To the lower metallic part, i, of the head-block is welded the front end of the metallic front part, D, of the reach, which reach curves downwardly, as shown in Fig. 2, until it again takes a horizontal direction at a. The rear end of this metallic part of the reach is forked, as shown, or otherwise constructed to 25 receive the wooden part or body of the reach b, which is firmly secured to the metallic part D of the reach, and which extends to the hind axle of the vehicle. The reach is shown single in Fig. 3, but the invention is equally applicable to a double reach. The upper ring, l, of the fifth-wheel E is secured by rivets or otherwise to the lower side of the metallic part i of the head-block, and by an arm, f, to the metal portion D of the reach. The lower ring, m, 35 of the fifth-wheel is secured to the front axle, G, in the usual manner.

F is the king-bolt which passes through the head-block, including the lower metallic part, i, of the same, and also above said metallic part i, through the metal part D of the reach. 45 Said king-bolt F is secured by a clip to the axle G, below which said clip is held, by nuts, or otherwise. As the king-bolt F passes through the lower metallic part of the head-block, and also through the metallic reach D, the wear 50 is taken up by said metal parts, and consequently the wooden upper portion, h, of the head-block is protected from wear. As the wooden part b of the reach is lowered by curving its metal part, D, as shown, the body of 55 the vehicle may also be lowered, which is a great advantage.

We claim—

1. The combination of the head-block A, consisting of an upper wooden portion, h, and 60 a lower metallic portion, i, with the fixed fifth-wheel plate l, movable fifth-wheel plate m, axle G, king-bolt F, and metallic reach D, said reach being welded to the lower metallic portion, i, of the head-block A above the plane of 65 the plate l, substantially as herein shown and described.

2. The combination of the head-block A, having lower metallic portion, i, with the fixed 70 fifth-wheel plate l, movable fifth-wheel plate m, axle G, king-bolt F, and metallic reach D, that is welded to the metallic portion i of the head-block above the plane of the plate l, and which is curved, substantially as and for the purpose herein shown and described.

LEONARD B. SNEDEN.
HORATIO N. HOLDEN.
